UNITED STATES PATENT OFFICE.

LOUIS F. BLUME, OF PITTSFIELD, MASSACHUSETTS.

PLAYING CARDS.

Application filed May 18, 1921. Serial No. 470,625.

To all whom it may concern:

Be it known that I, LOUIS F. BLUME, a citizen of the United States, residing at Pittsfield, in the county of Berkshire and 5 State of Massachusetts, have invented certain new and useful Improvements in Playing Cards, of which the following is a specification.

My invention relates to playing cards; 10 more particularly my invention relates to cards adapted for games simulating base ball.

The object of my invention is to provide a deck of cards with which games may 15 be played having more of the chances and hazards of genuine base ball, than has heretofore been possible.

Prior to my invention, in devising decks of cards adapted for games intended to 20 simulate base ball, some standard card or other game was not infrequently taken as a pattern, and a base ball nomenclature applied as far as possible, particularly to the cardinal plays; the deck devised being 25 marked and otherwise arranged to suggest the new nomenclature.

The fact that another game was taken as a pattern generally introduced so many 30 foreign elements into the card game intended to simulate base ball that in essentials it was not base ball and could not win devotees in spite of its base ball nomenclature.

Still other card games have been proposed 35 intended to simulate base ball without particularly patterning after any standard game. The cards for these games while introducing a base ball nomenclature as played, still were not adapted for playing 40 without some rule or rules introducing an element distinctly foreign to base ball; accordingly they have failed to acquire any marked following among gamesters.

The playing cards of my invention, on 45 the other hand, have been devised with special reference to standard base ball as played by the big leagues with reference to the sides or nines which play, to the infield, the outfield, the base runners, and to 50 the plays themselves which constitute the game. With my deck of cards, games may be played which simulate in every respect the minutia of each play affording records of errors, batting averages and the like in 55 the course of the game. The base ball nomenclature therefore naturally applies as

a matter of course. My deck accordingly yields a game of great interest and affords much amusement.

For a more complete understanding of 60 the nature and objects of my invention reference should be had to the following detailed description taken in connection with the accompanying drawing in which:

Figs. 1 to 9 show cards typical of the 65 various suits of which a deck is composed in accordance with my invention.

As indicated in the drawing, the deck of cards of my invention, which is adapted 70 for playing games simulating base ball, is composed of nine suits, each of the suits representing one of the nine players on a side; such suits being designated both by suitable design and insignia.

Fig. 1 shows a card designed to represent 75 the left fielder's suit. The salient feature of its design is a diamond on its face. The insignia LF is applied to the usual upper left-hand and lower right-hand corners to designate this suit; the card preferably bearing other insignia further to suggest this suit, as for instance by coloring the upper left-hand and lower right-hand corners as indicated.

Fig. 2 similarly shows a card designed to 80 represent the center fielder's suit. It is characterized by a diamond design on its face, and has designating insignia on its corners comprising CF on the upper left-hand and lower right-hand corners. All 85 four corners are also preferably colored as indicated further to make this suit readily distinguishable to the eye.

Fig. 3 shows a card designed for the 90 right fielder's suit, bearing again a diamond 95 design on its face and having suitable insignia on its corners comprising the letters RF on the upper left-hand and lower right-hand ones respectively. The upper right-hand and lower left-hand corners also 100 preferably bear other insignia as by having them colored as indicated.

In order to apportion properly the result of certain plays, as for instance to determine the number of bases stolen by a 105 base runner on a play simulating the failure of a baseman to catch the ball coming to him, I find it desirable to assign to certain suits or groups of suits, different group playing values. This is best accomplished 110 for playing purposes by like colorings on all suits belonging to the same group.

I have selected the fielder's suit to comprise one group and visually indicate this grouping by the use of green coloring on their corners as indicated by the hatching.

5 A second group is represented by the pitcher's, catcher's and short stop's suits shown respectively in Figs. 4, 5, and 6. For this group, I prefer black coloring. In design these suits are also characterized by the use of diamonds on their faces as shown. A card of the pitcher's suit is shown in Fig. 5, which, in addition, bears P's as designating insignia on its corners. A card of the catcher's suit is shown in Fig. 6 and bears 10 C's as the designating insignia on its corners. A card of the short stop's suit is shown in Fig. 7 and bears SS's as the designating insignia on its corners.

15 The third and last group of suits comprises the basemen's suits for designating which I prefer red coloring denoted by the vertical hatching on the cards shown in Figs. 7, 8 and 9.

20 In design these suits are again characterized by diamond designs on their faces. A card of the third baseman's suit is shown in Fig. 7 which bears three diamonds one within the other on its face; such card also having designated insignia on its corners 25 comprising the letters BBB on its upper left-hand and lower right-hand corners.

25 Fig. 8 similarly shows a card of the second baseman's suit having two diamonds one within the other on its face with designating 30 insignia comprising letters BB on its upper left-hand and lower right-hand corners, while Fig. 9 shows a card of the first baseman's suit, bearing but a single diamond on its face and having letters B as designating 35 insignia on its corners.

40 In my deck of nine suits there are six cards to the suit, or fifty-four cards in the whole deck. The cards of a suit are distinguished serially from each other preferably by numerals 1 to 6 inclusive as illustrated in the drawing. These numerals should be applied both to the corners and to the face of the card as shown in order to facilitate playing. Games simulating base ball can be played 45 with the deck which I have described by observing the following general playing rules; the use of a playing board bearing the representation of a base ball diamond when playing greatly adding to the realism of the 50 game.

55 Two or more parties may play, four parties making the best game; accordingly I will describe the game as played by four parties.

60 To play, the cards are shuffled and dealt among the four players, partners sitting opposite each other. The side which deals are preferably at the bat, while the others are in the field. It adds interest to the 65 game to give the side in the field materi-

ally more cards than the side at the bat. In dealing, I prefer to give each of the partners in the field fifteen cards while the partners at the bat receive only twelve each.

70 The side in the field (generally the player to the left of the dealer) leads off by playing a card representing the pitched ball; the play passing in rotation around the board. The pitcher may play any card, the nature of the play being determined by the card 75 number and not by suit. Playing a 2, 3, 4, 5 or 6 card may be styled a fair throw over the plate. In general, it is preferable to play the higher numbers, since, as will become evident by playing the game, these are 80 more difficult for the batter to hit.

If the pitcher play a card marked 1, the play is styled a ball.

85 When a fair throw, as above described, has been delivered by the pitcher, the nature of the play is determined by the card which the batter plays. In the event that the pitcher's suit is followed with a numerically high card, the batter provisionally scores a one base hit if his card is one point higher; 90 a two base hit if his card is two points higher; a three base hit if his card is three points higher; and a home run if his card is four points higher. In the event that the 95 pitcher's card is followed with a numerically lower card he scores a foul strike or a foul ball after the 2nd strike. Should, however, the batter play a card of a different suit, he makes a strike. In the event that the pitcher has played a card marked 100 1, the batter cannot play unless he has a card marked 2 of the same suit, which when played indicates in accordance with this game that he has been hit by the ball and he takes first base. Lacking such card the 105 batter does not play, and should say "Play ball" to indicate that the pitcher should play another card.

110 When the batter makes a provisional base hit, as described above, the fielder by playing the proper card, puts the batter out at his base. This is effected by playing the card numerically equal to the card played by the batter of the suit corresponding to the base to which the batter is running. For 115 example, assume that the pitcher has played as his pitched ball, the card marked LF-4; and that the batter next in order played the card marked LF-6. This card is two points higher than the pitched card and of the 120 same suit so that a provisional two base hit results. If now the fielder play a card marked BB-6, this card is numerically equal to the batter's card and corresponds in suit of the base to which the batter is running. The fielder thus puts the runner out. In the event the fielder cannot make such a play he should say "Safe" and place the 125 batter's card on the base earned.

130 When the batter has made a foul strike or

a foul ball, the fielder can catch the foul ball (foul out) by playing a card numerically equal to the batter's card in either of the suits marked B, BBB or C. If he cannot 5 do this, he should say "Play ball".

All base runners in this game are advanced as many bases as are earned by the batter. Thus, if there is a base runner on 10 2nd base and a one base hit is scored, the base runner advances to 3rd base; if a two base hit is scored, he comes home. All base 15 runners may be put out at the base they are approaching by the fielder playing the base card equal in number to the base runner's card. Thus, for example, if the base runner 20 is a card marked 5 and he is advancing to 3rd base, he may be put out at 3rd base by the fielder playing the BBB-5. If the base runner is advancing to home plate, he can be put out by the fielder playing C-5.

By the observance solely of the above simple rules an excellent game simulating base ball may be played, but in order to make the 25 game more completely resemble the game of base ball, the following additional rules should be observed.

With a man on base, a steal may be simulated as follows:—The ball having been pitched, the batter plays the same suit as the 30 card representing base runner. The steal card is placed above the base runner's card and both are advanced to the next base. The batter is credited with a strike or a ball depending upon the pitcher's card. The 35 fielder effects the putting out of the card stealing to a base by playing a card in the suit representing the base gained and which corresponds in value to or is greater than that of the steal card. If the fielder cannot 40 play such card, the steal card should be declared "safe".

A fair throw having been delivered by the pitcher, the batter can simulate a fly ball or 45 bunt by playing a card of the same number and same color as the pitcher's card. The nature of the fly is determined by the color of the cards. Thus, an outfield fly results by playing green cards, an infield fly by playing red cards, and a bunt by playing black cards.

50 A fly or bunt having been made by the batter, the fielder puts the batter out by playing any card of the batter's suit. In the case of a fly, this means that the ball has been caught, and in the case of a bunt, it means that the batter was not able to reach 55 1st base. In the event that the fielder fails to put the batter out according to this rule, the batter earns 1st base. If the fielder fails to catch the fly ball in accordance with this 60 procedure, he determines the base earned by the batter by discarding a base suit of any number, the suit marked B giving the batter first base; the suit marked BB giving the batter second base; and the suit marked 65 BBB giving the batter third base.

In the event that the fielder cannot catch the outfield fly, nor can play a base suit, the batter comes home.

When a bunt is made, all base runners advance one base even though the batter is put out. In no case, however, can a runner on 70 third base come home when a bunt is made unless forced. When an infield or outfield fly is made, base runners advance only when the fly is not caught. Base runners advance 75 as many bases as are earned by the batter. An exception to this rule is the sacrifice fly, which is an outfield fly with a man on third base. In this case, the man on third base comes home, regardless of whether the fly 80 is caught out by a fielder. Moreover, the base runner cannot be put out at home plate. With the exception of a sacrifice fly, base 85 runners can be put out at the bases they are approaching by playing thereon a card equal in value of a suit corresponding to the base approached.

These rules, of course, may be still further elaborated upon to simulate every minutia in a play in the game of base ball as played 90 by the big leagues; or they be further simplified as the case may be at the convenience of the players when desired.

Having now described an embodiment of my invention which is at present the best 95 means known to me for carrying the same into effect, I would have it understood that this is merely illustrative and that I do not mean to be limited thereby to the precise 100 details shown, nor restricted in the choice of recognized equivalents except as defined in my claims hereunto annexed.

What I claim as new and desire to secure by Letters Patent of the United States is:—

1. A deck of playing cards divided into 105 nine suits having designating insignia corresponding to a player on a base ball nine, each card bearing a diamond design; the suits being similarly cross divided and grouped by three's, each group having a distinguishing color.

2. A deck of playing cards divided into 110 nine suits having designating insignia corresponding to a player on a base ball nine, each card bearing a diamond design; each suit having six cards, the suits being similarly cross divided and grouped by three's and having a group distinguishing color.

3. A deck of playing cards divided into 115 nine suits having designating insignia corresponding to a player on a base ball nine, there being in all fifty-four cards each of which bears a diamond design on its face; the suits corresponding to left field, center field, and right field, being grouped together 120 and distinguished by the use of green coloring, the first baseman's, second baseman's and third baseman's suits forming a second group distinguished by the use of red coloring, the pitcher's, catcher's and short stop's suits 130

forming a third group distinguished by the use of black coloring.

4. A deck of playing cards divided into nine suits having designating insignia corresponding to the players on a base ball nine, said suits having additional common designating insignia for similarly cross-dividing the suits into a plurality of similar ranks, whereby plays may be simulated corresponding to the quality of the ball pitched.

5. A deck of playing cards comprising fifty four cards divided into nine suits having designating insignia corresponding to

the players on a base ball nine, the suits being similarly cross divided into a plurality of ranks each having identical designating numerals whereby plays may be simulated corresponding to the quality of the ball pitched; the suits being further divided into groups distinguished by colors, each group containing cards of all the ranks designated by the cross division.

In testimony whereof I have affixed my signature, this 9th day of May, 1921.

LOUIS F. BLUME.
